UNITED STATES PATENT OFFICE.

JEREMIAH J. GREENE, OF PHILADELPHIA, PENNSYLVANIA.

DESIGN FOR A CONDIMENTS-HOLDER.

No. 39,956.

Specification for Design.

Patented May 4, 1909.

Application filed December 30, 1908. Serial No. 470,113. Term of patent 7 years.

To all whom it may concern:

Be it known that I, JEREMIAH J. GREENE, a citizen of the United States, residing at Philadelphia, in the county of Philadelphia and State of Pennsylvania, have invented a new, original, and ornamental Design for Condiment Holders, of which the following is a specification, reference being had to the accompanying drawing, forming part thereof.

The figure is a perspective view of a condiment holder showing my design.

I claim:

The ornamental design for a condiment holder as shown.

JEREMIAH J. GREENE.
